UNITED STATES PATENT OFFICE.

MICHAEL F. HÄBERLE, OF WOODHAVEN, NEW YORK.

DRAWING BOARD AND STAND.

1,372,810.

Specification of Letters Patent. Patented Mar. 29, 1921.

Application filed December 9, 1919. Serial No. 343,688.

To all whom it may concern:

Be it known that I, MICHAEL F. HÄBERLE, citizen of the United States, residing at Woodhaven, in the county of Queens and 5 State of New York, have invented certain new and useful Improvements in Drawing Boards and Stands, of which the following is a specification.

This invention relates to an improved 10 drawing board and stand and has as one of its principal objects to provide an arrangement wherein the drawing board will be constructed to carry a supply roll and wherein the drawing paper may be shifted across 15 the board from said roll.

A further object of the invention in this connection is to provide a construction wherein drawing paper will be held taut across the board so as to eliminate the necessity 20 for the use of thumb tacks.

A still further object of the invention is to provide a drawing board having a bed plate or board proper which will not warp and wherein said plate may, as occasion may 25 demand, be readily renewed.

A still further object of the invention is to provide a construction wherein the board may be adjustably tilted and may also be adjustably rotated.

30 And the invention has as a still further object to provide an arrangement wherein the effective height of the stand may be adjustably varied for either raising or lowering the board.

35 Other and incidental objects will appear hereinafter.

In the drawings:

Figure 1 is a perspective view of my improved drawing board and stand,

40 Fig. 2 is a longitudinal sectional view, the board being shown in position lying flat upon the stand,

Fig. 3 is a transverse sectional view taken medially through the board and stand,

45 Fig. 4 is a perspective view illustrating the board and associated parts in detail,

Fig. 5 is a transverse section taken on the line 5—5 of Fig. 4, and

50 Fig. 6 is a fragmentary perspective view illustrating the plates carried by certain of the legs of the stand whereby the effective height of the stand may be adjustably varied.

In carrying the invention into effect, I 55 employ a stand which is constructed of end sections 10 and side sections 11. Each of the

end sections includes a pair of legs joined by spaced rails and, in like manner, each of the side sections also includes a pair of legs joined by spaced rails. Countersunk in the 60 legs of the side sections are, as particularly shown in Fig. 6, vertical plates 12 from the upper end portions of which project studs 13 and secured to the legs of the end sections are angle plates 14 in each of which is 65 formed a series of openings 15. The openings 15 of the plates 14 are adapted to selectively receive the studs 13 and formed through the angle plates are vertical slots 16 adapted to freely receive clamping screws 70 17 therethrough, these clamping screws being threaded through the lower end portions of the plates 12. Thus, as will be perceived, the studs 13 of the end sections may be selectively engaged in the series of openings 15 of the plates 14 of the side sections 75 for adjustably elevating the side sections, as shown in Fig. 1, upon the end sections, when the clamping screws 17 may be tightened for securing the side sections in elevated position. In this way, the effective height of the stand may be adjustably varied.

The drawing board employed includes a frame comprising side rails 18 and end rails 19, a mullion 20 extending transversely between the side rails at a point substantially midway between the end rails. Suitably secured to the end rails are channel strips which, for convenience, have been indicated at 21 and 22 respectively. Secured to the 90 side rails of the frame are longitudinal cleats 23 provided with beveled inner edges and overlying the frame to extend between the channel strips thereof is the bed plate 24 of the board. This bed plate is provided 95 with beveled side edges mating with the beveled inner edges of the cleats so that the plate is thus firmly held in position upon the frame. Screws or other suitable fastening devices are employed for securing the cleats 100 so that, as will be seen, by removing either of the cleats the plate may be readily removed, this construction providing an arrangement whereby the plate may be renewed from time to time as occasion may demand. The plate is preferably constructed of what is generally known as composition board although other approved material may be employed. However, in providing a plate of the character indicated, said plate 105 will not warp.

In the strip 21 is formed a vertical slot

25 to freely receive the vertical flange of a clamping plate 26, so that the horizontal flange of said plate will, as particularly shown in Fig. 2, overhang the channel of the strip. Depending from the clamping plate adjacent opposite ends thereof are studs 27 which are freely received through the strip and through suitable wear plates 28 connected thereto, and threaded upon the 10 studs are suitable wing nuts 29 confronting the wear plates. As will be observed upon reference to Fig. 4, the upper end portions of the studs extend over the horizontal flange of the clamping plate, providing a 15 reinforcement therefor. Secured to the ends of the channel strip 22 are bearing plates which, for convenience, have been indicated at 30 and 31 respectively. These bearing plates are provided at their inner 20 sides with laterally directed arcuate stop flanges 32 lying within the channel of the strip and, as will be observed, the end portions of said flanges at the upper side of the channel are rounded off. Journalized 25 upon the bearing plates to lie within the channel of said strip is a take-up roller 33 extending axially between said flanges. At one end the roller is equipped with a ferrule 34 journaled through the plate 30 while at its opposite end, said roller is equipped with a ferrule 35 from which projects a suitable trunnion journaled through the plate 31. Fixed upon said trunnion at the outer side 30 of the plate is a ratchet disk 36 and pivoted 35 upon the plate to cooperate with said disk is a pawl 37. Seated against the disk 36 is a winged turning head 38 also suitably fixed to the trunnion of the ferrule 35 so that by turning said head the roller 33 may be rotated. Formed in said roller at one side 40 thereof is a longitudinally extending channel 39 and normally engaged in this channel is the vertical flange of a substantially T-shaped locking strip 40. At the mouth of the slot 39 the roller is flattened to seat the horizontal flange of the locking strip and, as will now be observed, this latter flange extends beyond the ends of the vertical flange of the strip to overlie the ferrules 34 45 and 35 of the roller. In use, a supply roll of drawing paper is placed within the channel of the strip 21, the paper strip 41 being wound about a suitable core 42. By removing the clamping plate 26 the supply roll 50 may, of course, be readily fitted in position and, as will be observed, by adjusting the wing nuts 29, the plate may be caused to bear against the roll for tensioning the roll within the channel of the strip. At its free 55 end, the paper strip is led across the slot 39 in the take-up roller when the locking strip 40 is, as shown in Fig. 5, fitted in position upon the roller for connecting the strip thereto. Then, by turning the roller, the 60 end portions of the strip will be moved into 65

coacting relation with the stop flanges 32 so that the strip will, while the first complete turn of the roller is made, be held upon the roller by said flange, the end portions of the strip riding upon the flanges and being held thereby flat against the ferrules of the roller. After the first complete turn of the roller is made, the paper strip will then overlie the locking strip so that the locking strip cannot then become dislodged from the roller. Accordingly, as will be seen, the turning head 38 may be operated to wind the paper strip from the supply roll across the bed plate of the drawing board onto the take-up roll and since the clamping plate 26 will retard unwinding of the supply roll while the ratchet disk 36 and pawl 37 will prevent counter-rotation of the take-up roll, the strip will be held taut lying flat against the bed plate. Accordingly, any necessity 85 for the use of thumb tacks will be eliminated while the paper strip may be readily shifted to present, as desired, a clean or unused surface over the bed plate of the board. 90

Removably rested upon the stand is a supporting frame for the drawing board. This frame includes a lower frame section 43 and a mating upper frame section 44. The frame section 43 is constructed to mate 95 with the top rails of the stand and is provided with depending side strips 45 adapted to coact with the outer faces of said rails so that said section will firmly seat upon the stand. At the forward side of the supporting frame, the sections thereof are 100 swingingly joined by suitable hinges connected to the forward side rails of said sections so that, as shown in Fig. 1, the upper section may be tilted upwardly and forwardly upon the lower section and to prevent possible accidental raising of the rear side portion of the lower section, the rail of this section carries a hook 46 engageable in an eye 47 upon the upper rail of the rear side 110 section of the stand. Extending between the side rails of the lower section 43 are spaced transverse mullions 48 in the upper edges of which are formed, at the rear end portions of the mullions, series of notches 115 49. The upper frame section carries a longitudinal mullion 50 and swingingly mounted upon this mullion is a prop 51, the spaced legs of which are adapted to coact at their free ends with the series of notches 49. Countersunk in the mullion 20 of the frame 120 of the drawing board is a plate 52 to which is fixed a post 53 depending from the plate and rotatably engaged through the mullion 50 of the upper frame section 44. Threaded upon the lower end portion of the post is a wing nut 54 and surrounding said post is a helical spring 55 held between washers 56. Thus, the post 53 will rotatably connect the drawing board with its supporting 125 130

frame while the wing nut 54 may be adjusted for tensioning the spring 55 so that the uppermost of the washers 56 will be held in binding contact with the lower face of the mullion 50 for frictionally resisting rotation of the board. Consequently, the board may, as suggested in Fig. 1, be rotatably positioned as desired when the board will be firmly held in such position, and by 5 swinging the frame section 44 upwardly upon the frame section 43, the drawing board may be adjustably elevated when the prop 51 will coat with the series of notches 49 in the mullion 48 of the lower frame 10 section for sustaining the board in inclined position. It will accordingly be seen that I have provided a particularly effective construction for the purpose set forth. The drawing board may, if desired, be readily 15 detached from its supporting frame while the board, together with said frame, may be bodily removed from the stand. Further, as will be clear, the stand may be easily collapsed so that when not in use the drawing 20 board and stand may be arranged to occupy 25 a minimum space.

Having thus described the invention, what is claimed as new is:

1. In a device of the character described, 30 a drawing board provided at one end with a channel for receiving a supply roll of paper, a plate adjustable vertically in said end of the drawing board and having an overhanging portion to bear upon the supply 35 roll within said channel whereby to tension the unwinding of a paper strip from the roll, and a take-up roller journaled upon the opposite end of the board and rotatable for winding the strip thereon extending 40 across the board from the supply roll.

2. In a device of the character described, 45 a drawing board having a channel formed in one portion thereof to receive a roll of paper, a clamping plate having an overhanging portion to bear upon the roll of paper, studs depending from said plate through the board, nuts adjustable upon said studs against the board to clamp the 50 plate upon the roll of paper whereby to tension the unwinding of a strip from the roll, and a take-up roller journaled upon

the board and rotatable for winding a strip thereon extending across the board from the supply roll.

55

3. In a device of the character described, a drawing board, means for supporting a supply roll of paper thereon, a take-up roller journaled upon the board and rotatable for winding a strip thereon extending across the board from the supply roll, means for connecting the paper strip with the take-up roller and freely removable from the roller, and stationary means on the board arranged to coat with said first 60 mentioned means for holding said first mentioned means against displacement from the the roller when the roller is rotated.

65

4. In a device of the character described, a drawing board, means for supporting a supply roll of paper thereon, stationary bearing plates carried by the board, a take-up roller journaled in and extending between said plates and provided with a longitudinal slot, a locking strip freely engageable in said slot for binding a paper strip therein, and means carried by the bearing plates to coat with said strip for holding the strip against displacement from the roller when the roller is rotated.

80

5. In a device of the character described, a drawing board, means for supporting a supply roll of paper thereon, bearing plates carried by the board, a take-up roller journaled in and extending between said plates 85 and provided with a longitudinal slot, a locking strip freely engageable in said slot for binding a paper strip therein, and arcuate flanges carried by said bearing plates to coat with the strip for holding the strip 90 against displacement from the roller when the roller is rotated.

6. In a device of the character described, in combination, a stand, a supporting frame resting thereon, a drawing board resting on the frame, a post depending from the board and rotatable in the frame, washers on the bolt below the frame, a spring coiled around the post between the washers, means for adjusting the tension of the spring, and means 95 carried by the frame for adjustably tilting the board.

In testimony whereof I affix my signature.

MICHAEL F. HÄBERLE. [L. s.]
